Inventor:
Herman C. Priebe,
By G. L. Cragg Attorney

UNITED STATES PATENT OFFICE.

HERMAN C. PRIEBE, OF BLUE ISLAND, ILLINOIS.

DRAFT GEAR.

Application filed September 5, 1919. Serial No. 321,931.

To all whom it may concern:

Be it known that I, HERMAN C. PRIEBE, a citizen of the United States, residing at Blue Island, in the county of Cook and State 5 of Illinois, have invented a certain new and useful Improvement in Draft Gears, of which the following is a full, clear, concise, and exact description.

My invention relates to draft gears of the 10 type employing inner and outer followers actuated by couplers, rockers individual to the followers and movable thereby, and means, operating through said rockers, for resisting the approach of the followers toward each other. This motion resisting 15 means is preferably in the form of spring mechanism, particularly where friction is not relied upon to resist the relative movement of the followers.

It is the object of my invention to improve the construction and arrangement of the component parts of the gear which have been named whereby the desired effectiveness in operation may be secured with the 25 most simple construction of gear.

In practising my invention I employ at least two or more sets of rockers, each set having one rocker individual to each follower and movable thereby. The two rockers 30 of each set interact by providing them with opposed engaging faces and are interposed between the motion resisting means which is subdivided into two elements each element being individual to a follower and in alignment with the other element and with both 35 followers. The engaging side of each rocker is formed with a projection, extending longitudinally of the gear, that overlaps the other whereby displacement of the 40 rockers is prevented. I preferably provide two such projections, spaced apart, upon one rocker and a single one upon the other that enters the space between the two projections.

I will explain my invention more fully by 45 reference to the accompanying drawings showing the preferred embodiment thereof and in which Figure 1 is a sectional view taken generally on line 1—1 of Fig. 2; Fig. 2 is a sectional view taken generally on line 50 2—2 of Fig. 1; Fig. 3 is a sectional view on line 3—3 of Fig. 1; Fig. 4 is a sectional view on line 4—4 of Fig. 1; Fig. 5 is a view illustrating some of the elements appearing in Fig. 1 but in changed positions; and Fig. 55 6 is a perspective view illustrating a fol-

lower and two rockers belonging to different sets and each individual to said follower.

Like parts are indicated by similar characters of reference throughout the different figures.

The coupler 1 has a coupler shank 2 to which the outer ends of a yoke 3 are secured by means of rivets or bolts 4. An outer follower 5 is engaged by the coupler butt 6 and is moved inwardly whenever the coupler is subjected to sufficient pushing strain. The inner follower 7 is engaged by the inner end of the coupler yoke 3 and is movable outwardly when the coupler is subjected to sufficient pulling strain. The extent to which the outer follower is movable outwardly is limited by the outer stops 8. The extent to which the inner follower 7 is movable inwardly is limited by the inner stops 9. All of 70 said stops are riveted against the center sills 75 that form a part of the underframe structure of a car equipped with the draft gear. The followers 5 and 7 are in the nature of spring barrels which house the cooperating 80 spring elements 11 and 12 of mechanism that is employed to resist the movement of either follower toward the other and to effect the return of the followers toward the stops respectively pertaining thereto.

One or more sets of rockers are disposed 85 between the followers. I have illustrated two sets of rockers, each set including a rocker 13 individual to the outer follower 5 and a rocker 14 individual to the inner 90 follower 7.

The outer follower 5 carries two upright 95 seats or mountings 5¹, one for each rocker 13 to rock upon. The inner follower 7, similarly, carries two upright seats or mountings 7¹ one for each rocker 14 to rock upon. The rockers thus turn in horizontal 100 planes and interact by being pressed in direct engagement by the springs 11, 12 of the motion resisting mechanism, these springs serving to oppose the relative movement of the followers by opposing the attendant follower effected rocking movement of the rockers. The rockers of each set, are formed with engaging faces whereby each rocker of a set causes the other 105 rocker of the same set to turn upon its seat or mounting. Each rocker has a part thereof which is in engagement with the seat provided upon the follower individual thereto curved to form a segment of a cyl- 110

inder, the seat upon the follower engaged thereby being similarly curved. By this construction each rocker has an axis of rotation which is substantially fixed with respect to the follower individual thereto. The aforesaid seats 5¹, 7¹ and the rockers engaging the same are placed upright, the follower 5 being provided with inner ledges 5² between which the rockers 13 are disposed and the follower 7 being provided with outer ledges 7² between which the rockers 14 are disposed, these ledges preventing the rockers from moving up and down materially.

15 The engaging face on each rocker is formed with a projection 16 extending longitudinally of the gear and engaging a face 15 on the other rocker. There are desirably two spaced apart projections 16 upon one rocker that receive the projection on the other rocker therebetween, the latter projection underlying one of the other two and overlying the other, each projection upon each rocker engaging the body portion of the other. By this arrangement the contacting surfaces are increased and the interleaving projections prevent the rockers from falling out.

20 By the arrangement illustrated each spring acts upon both rockers of a set and the rockers form a motion resisting means between the springs, all of these elements thus being interacting when either follower is in motion. Moreover, the entire structure is very compact, being embraced between the sides of the yoke and the center sills.

25 While I have herein shown and particularly described the preferred embodiment 40 of my invention I do not wish to be limited to the precise details of construction shown as changes may readily be made without departing from the spirit of my invention, but having thus described my invention I

claim as new and desire to secure by Letters Patent the following:—

1. A draft gear including a coupler; inner and outer followers actuated thereby and movable each toward the other; springs, one individual to each follower, for resisting the approach of the followers toward each other; and two rockers having opposed engaging faces, one rocker being individual to each follower and actuatable thereby, said rockers being interposed between and engaged by said springs to maintain the rockers in contact and resist follower effected movement thereof, each rocker being formed with a projection extending longitudinally of the gear one projection overlying the other, each projection upon each rocker engaging the body portion of the other rocker.

2. A draft gear including a coupler; inner and outer followers actuated thereby and movable each toward the other; springs, one individual to each follower, for resisting the approach of the followers toward each other; and two rockers having opposed engaging faces, one rocker being individual to each follower and actuatable thereby, said rockers being interposed between and engaged by said springs to maintain the rockers in contact and resist follower effected movement thereof, one rocker being formed with one projection extending longitudinally of the gear and the other rocker being formed with two such projections that are spaced apart and receive the first projection therebetween, said first projection underlying one of the other two projections and overlying the other, each projection upon each rocker engaging the body portion of the other rocker.

In witness whereof, I hereunto subscribe my name this 26th day of August A. D., 1919.

HERMAN C. PRIEBE.
